(57) **CLAIM**

The ornamental design for a jaw pad cover, as shown and described.

DESCRIPTION

FIG. 1 is a perspective view of a jaw pad cover showing our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a perspective view of a second embodiment thereof;

FIG. 9 is a left side elevation view thereof;

FIG. 10 is a right side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The indicia (FIGS. 6, 7, 13 and 14) and fasteners (FIGS. 1, 3-8, 10-14) shown in broken lines and the jaw pad (FIGS. 1, 3, 8 and 10), form no part of the claimed design. The dashed lines in FIGS. 1, 4-8 and 10-14 represent stitching which is claimed.
